(57) **CLAIM**

The ornamental design for a block body for integrated valve unit, as shown and described.

DESCRIPTION

FIG. 1 is a perspective view of a block body for integrated valve unit when seen from the bottom and left of the front, showing my new design;

FIG. 2 is a front elevational view thereof;

FIG. 3 is a rear elevational view thereof;

FIG. 4 is a top plan view thereof;

FIG. 5 is a left side elevational view thereof;

FIG. 6 is a right side elevational view thereof; and,

FIG. 7 is a cross section taken across FIG. 2 along line 7—7. A bottom plan view is omitted as it appears symmetrical with the top plan view.
